UNITED STATES PATENT OFFICE.

JOHN A. FRASER, OF BENTON HARBOR, MICHIGAN, ASSIGNOR TO BAKER-VAWTER COMPANY, OF BENTON HARBOR, MICHIGAN, A CORPORATION OF MAINE.

DESIGN FOR A DESK-TRAY.

44,999.

Specification for Design.

Patented Dec. 9, 1913.

Application filed July 9, 1913. Serial No. 778,220. Term of patent 7 years.

To all whom it may concern:

Be it known that I, JOHN A. FRASER, a citizen of the United States of America, and a resident of Benton Harbor, in the county of Berrien and State of Michigan, have invented a new, original, and ornamental Design for Desk-Trays, of which the following is a specification, reference being had to the accompanying drawing, forming part thereof.

The figure is a perspective view of a desk tray showing my new design.

I claim:

The ornamental design for a desk tray, as shown.

JOHN A. FRASER.
